UNITED STATES PATENT OFFICE.

KARL ENDLE, OF SANDUSKY, OHIO.

DESIGN FOR A SPITTOON-COVER.

SPECIFICATION forming part of Design No. 28,862, dated June 14, 1898.

Application filed January 26, 1898. Serial No. 668,073. Term of patent 7 years.

To all whom it may concern:

Be it known that I, KARL ENDLE, a citizen of the United States, residing at Sandusky, in the county of Erie and State of Ohio, have 5 invented and produced a new and original Design for Spittoon-Covers; and I do declare the following to be a full, clear, and exact description of the same, reference being had to the accompanying drawings, forming a part 10 thereof.

Figure 1 is a plan view showing my design. Fig. 2 is a cross-sectional view of the same.

The drawings referred to represent a plan view of a spittoon-cover, showing my new design.

15 My design is circular in outline with a series of divergent arms *a* extending from the periphery thereof. Within the periphery and arranged around a central opening *b* are a

number of small circular openings *c*. The 20 diameter of the small openings is about one-half of the central opening. The cover is concave, as shown.

The material feature of my design for spittoon-covers is the shape and configuration of 25 the unitary article made the subject of the accompanying illustration.

Having described my invention, what I claim as new, and desire to secure by Letters Patent, is—

The design for a spittoon-cover, as herein shown and described.

In testimony whereof I affix my signature in presence of two witnesses.

KARL ENDLE.
